UNITED STATES PATENT OFFICE.

WILLIAM B. HALL, OF CHICAGO, ILLINOIS, ASSIGNOR TO UNION RAILWAY EQUIPMENT COMPANY, OF CHICAGO, ILLINOIS, A CORPORATION OF ILLINOIS.

COUPLER RELEASE RIGGING.

Application filed March 7, 1925. Serial No. 13,694.

To all whom it may concern:

Be it known that I, WILLIAM B. HALL, a citizen of the United States, residing at Chicago, in the county of Cook and State of Illinois, have invented certain new and useful Improvements in Coupler Release Rigging, of which the following is a specification.

The object of this invention is to provide means for raising the lock in the coupler when it is desirable to uncouple the cars. This action throws the coupler knuckle open and permits the cars to separate.

The mechanism of the present invention is designed to afford a considerable leverage which is necessary in order to raise the coupler lock and force the knuckle of the coupler open with a minimum of hand power on the end of the operating lever.

In use, it is frequently necessary for the operator to stand on the sill step at the corner of the car, particularly when the car is in motion, and from this position it is easier for him to pull up on the lever than to push down. When, however, a man is standing on the ground and attempts to operate the release rigging, it is naturally more convenient for him to push down than to pull, and the rigging of the present invention is designed to be operated with equal facility by either method.

The invention is also directed to the means for guiding the lever to keep it in alignment and to afford sufficient clearance around the lever to conform to the safety appliance rules. The lever mechanism is also designed to afford a greater degree of leverage than can be obtained in the use of a one piece lever, and to improve the construction and arrangement of the device as a whole.

In the drawings:

Figure 1 is an elevation of the end of a car showing the locking pin lowered and the coupler locked; and

Fig. 2 is a plan view of the same.

The drawings represent the coupler head 10 outwardly projecting from a base plate or mounting 11 secured to the end sill 12 of a car. The usual sill step 13 hangs from the corner of the car in close proximity to the operating lever 14, which is of bell crank formation and provided at its inner end with an upper extension or short arm 15.

The lever is pivoted at its elbow upon a dowel pin 16 which extends upwardly from a bracket 17 bolted to the end of the car, which bracket stands away from the car and is provided with a segmental shaped guide plate 18 having an outwardly spaced arcuate guide strap 19 behind which the lever operates within the limits afforded by the strap. The lever normally occupies the medial position, shown with the short arm of the lever extending vertically, and this arm is perforated to receive a ring shaped link 20, which connects with the outer end of a fulcrum lever 21, which is carried by a dowel pin 22 on the outer end of a fulcrum bracket 23, the dowel being of sufficient length to permit the lever to slide laterally to the degree necessary to accommodate any lateral motion which may take place on the inner end of the lever which is connected with the coupler lock.

It will be noted that the fulcrum lever is pivoted at a point comparatively near to its outer end, so that a comparatively short vertical movement imparted to the outer end of the lever will be correspondingly magnified in degree at the inner end. The inner end of the lever is offset away from the car to a degree necessary to bring the inner end into alignment with the coupler lock pin 24, and the inner end of the lever terminates in a round hooked extension 25, which fits freely through the eye of the pin and is of sufficient length to accommodate any lateral movement of the coupler head in a direction lengthwise of the fulcrum lever.

In use, either an up or down motion of the outer end of the hand lever will impart a pull to the link which connects with the outer end of the fulcrum lever, and this relatively short vertical motion will be amplified sufficiently at the inner end to raise the lock pin and release the coupler knuckle. This method of applying the uncoupling apparatus to the end of the car comprises a lever having direct connection to the coupler lock without the use of bolts, clevises, key bolts, cotter pins, etc., as directed by the A. R. A. rules. It is also applied so that there is ample clearance between the lever and the end of the car for the provision of a brake shaft of any approved design. The link connecting the hand lever and the ful-

crum lever is preferably made of $\frac{3}{4}$ inch round steel, which eliminates the necessity for key bolts, cotter pins, etc., and at the same time provides freedom for the short arm of the hand lever in performing the arcuate movements to which it is subjected.

I claim:

1. In a coupler release rigging in combination with the vertically movable locking pin, a pivoted pin-operating lever having its inner end so connected with the pin as to impart vertical movements thereto, and a pivoted hand lever having its inner end standing in substantially right angle relation to the outer end of the pin-operating lever and so connected therewith as to impart vertical pin lifting movements thereto by a movement of the operating lever in either direction, substantially as described.
2. In a coupler release rigging in combination with the vertically movable locking pin, a pivoted pin-operating lever having its inner end so connected with the pin as to impart vertical movements thereto, and a pivoted hand lever of bell crank formation having its inner end standing vertically with relation to and being connected to the outer end of the first named lever in a manner to impart pin lifting movements thereto by movement of the hand lever in either direction, the outer end of the hand lever extending horizontally to a point in close proximity to the side of the car, substantially as described.
3. In a coupler release rigging in combination with a vertically movable locking pin, a pin-operating lever engaging the upper end of the pin, said lever being pivoted at a point to provide a long inner arm and a short outer arm, and a hand lever pivoted to provide a short inner arm and a long outer arm, the short arm of the hand lever standing in right angle relation to the outer end of the pin operating lever and connected thereto to impart vertical pin lifting movements thereto by movement of the hand lever in either direction, substantially as described.
4. In a coupler release rigging in combination with a vertically movable locking pin, a pin-operating lever engaging the upper end of the pin, said lever being pivoted at a point to provide a long inner arm and a short outer arm, and a hand lever pivoted to provide a short inner arm and a long outer arm, the short arm of the hand lever standing in right angle relation to the outer end of the pin operating lever and connected thereto to impart vertical pin lifting movements thereto by movement of the hand lever in either direction, said connection being afforded by means of a link, substantially as described.
5. In a coupler release rigging in combination with a vertically movable locking

pin, a pin-operating lever engaging the upper end of the pin, said lever being pivoted at a point to provide a long inner arm and a short outer arm, and a hand lever pivoted to provide a short inner arm and a long outer arm, the short arm of the hand lever standing in right angle relation to the outer end of the pin-operating lever and connected thereto to impart vertical pin lifting movements thereto by movement of the hand lever in either direction, said connection being afforded by means of a ring shaped link, substantially as described.

6. In a coupler release rigging, in combination with a vertically movable locking pin, a pin operating lever having its inner end vertically movable and in engagement with the pin, a pivot on the end of the car engaging an intermediate portion of said lever, a hand lever having its inner end in proximate relation to the outer end of the pin operating lever, a pivot on the end of the car engaging an intermediate portion of the hand lever, and a connecting member between the proximate ends of the two levers, the pivots being so disposed in relation to one another as to maintain the proximate ends of the two levers in substantially right angle relation to one another in the medial position when the inner end of the pin operating lever is lowered, whereby a swinging movement of the inner end of the hand lever in either direction away from the medial position will effect a lifting of the inner end of the pin operating lever, substantially as described.

7. In a coupler release rigging in combination with a vertically movable locking pin, a horizontally disposed pin-operating lever pivoted to the car at a point to afford a relatively long inner arm and a relatively short outer arm, the inner arm having sliding engagement with the locking pin, and the pivotal mounting for the lever affording limited freedom for lateral movement to the lever, and a hand lever of bell crank formation pivoted to the car and having a short vertically extending inner arm and a long horizontally extending outer arm, the inner arm being connected with the short outer arm of the pin-operating lever, in a manner to impart pin lifting movements thereto by movement of the hand lever in either direction, substantially as described.

8. In a coupler release rigging in combination with a vertically movable locking pin, a horizontally disposed pin-operating lever pivoted to the car at a point to afford a relatively long inner arm and a relatively short outer arm, the inner arm having sliding engagement with the locking pin, and a hand lever of bell crank formation pivoted to the car and having a short vertically extending inner arm and a long horizontally extending outer arm, the inner arm being
